FIG. 2.

FIG. 3.

W. H. HETZEL
INVENTOR
BY
Donald Henderson
ATTORNEY

UNITED STATES PATENT OFFICE.

WILLIAM H. HETZEL, OF SYRACUSE, NEW YORK.

NUMBER-PLATE.

1,323,694.

Specification of Letters Patent.

Patented Dec. 2, 1919.

Application filed November 5, 1918. Serial No. 261,202.

To all whom it may concern:

Be it known that I, WILLIAM H. HETZEL, a citizen of the United States of America, and resident of Syracuse, in the county of 5 Onondaga, in the State of New York, have invented new and useful Improvements in Number-Plates, of which the following, taken in connection with the accompanying drawings, is a full, clear, and exact description.

This invention relates to certain improvements in number plates adapted to be attached in a conspicuous place to buildings to indicate the street number of the premises upon which the building is located and involves the use of a rectangular one-piece sheet metal frame and one or more separate sheet metal figures or numerals mounted thereon so as to be clearly visible across the 20 opening therein.

The main object is to provide a device of this character which may be made and sold at a sufficiently low cost to enable it to be standardized for general use.

Another object is to enable any one of a 25 series of the sheet metal figures or numbers to be easily and quickly placed in its proper position upon the frame or removed therefrom without disturbing either of the other 30 figures or numbers.

A further object is to assure the symmetrical spacing of the several figures or numbers in the frame without the use of extra spacing members so that when assembled, the numbers will be in uniformly 35 spaced relation with their front faces in substantially the same vertical plane as that of the front face of the frame.

Other objects and uses relating to specific 40 parts of the device will be brought out in the following description.

In the drawings:—

Figure —1— is a perspective view of a 45 number plate embodying the various features of my invention.

Fig. —2— is a transverse vertical sectional view taken on line 2—2, Fig. —1—.

Fig. —3— is a perspective view from the rear of one of the detached figures or numbers showing its attaching members in position for application to the frame.

As illustrated this number plate comprises a substantially rectangular frame —A— and a plurality of, in this instance 50 three, separate figures or numerals —a— having individual means of attachment to

the frame for holding them in uniformly spaced relation across the opening in said frame.

The frame —A— is preferably made from 60 a single piece of sheet metal and is composed of parallel lower and upper horizontal rails —1— and —2— and upright parallel end rails —3— and —4— united to the corresponding ends of the horizontal rails by 65 rounding corners —5—, the end rails and also the top and bottom rails being arranged in spaced relation to form an intervening substantially rectangular and horizontally elongated opening —6—.

The opposite side and end rails including the rounding corners of the frame are of substantially the same concavo convex sectional form throughout their lengths and are arranged with their convex sides to the 75 front so that the rear concave side forms a marginal groove —g— extending the entire length and width of the frame to be utilized for a purpose presently described.

The lower and upper rails —1— and —2— 80 are provided with a series of, in this instance, three sets of slots —a'— one set for each figure, those of the several sets being arranged in uniformly spaced relation lengthwise of the frame, the space between 85 the end slots and inner edges of the end rails being approximately equal to one half the space between the slots of the several sets whereby the spacings of the figures relatively to each other and to the end rails will 90 be approximately equal.

The figures or numbers —a— are preferably standardized as to vertical height and transverse width, the height being substantially equal to the corresponding height of 95 the opening —6— while the width is such as to permit the use of a plurality of the figures side by side in uniformly spaced relation relatively to each other and to the end rails —3— and —4— whereby each figure 100 stands out clearly across the open space in the frame with a clear space practically surrounding it which materially increases its visibility both in daylight and dark.

Each figure or numeral is made of thin 105 sheet metal stamped or pressed in such a manner as to form rearwardly projecting ribs —7— extending along and around the entire marginal edge thereof for reinforcing purposes and also to give the front faces 110 of the figure a more or less raised appearance.

The central portions of the extreme lower and upper rearwardly projecting ribs or flanges —7— of each figure are provided with relatively narrow integral tongues —8— capable of being easily bent.

The intermediate portions of these tongues —8— are offset forwardly or outwardly to form shoulders or seats —9— adapted to rest against the inner front corners of the lower and upper rails to properly center the figures between said rails and also to assist the tongues —8— in removing the figures in the frame against relative movement thereon particularly when the tongues are clenched or bent against the backs of the rails within the grooves —g— and at the same time permitting the figures to be readily removed by simply rebending the free ends of the tongues —8— at substantially right angles to the plane of the main body thereof as shown in Fig. —3—, the function of the shoulders —9— being clearly illustrated in Fig. —2—.

In placing the sheet metal numerals in operative position within the frame the tongues —8— of each numeral are registered with and passed through their corresponding slots —a— and bent or clenched against the backs of their respective rails within the lengthwise grooves —g— thereof, to hold the numerals in fixed relation to the frame.

This manner of clenching the tongues against the backs of the rails not only conceals the major portions thereof from view but also enables the back of the frame to be fastened flatwise and firmly against the portion of the building to which it is applied and prevents malicious removal of the nu-

merals when the frame with the numerals 40 thereon are secured in place.

If, however, it should be desired at any time to remove any one of the numerals it would be necessary to remove the frame from the building, unless otherwise suspended as by hooks or hinges, whereupon the tongues may be rebent to their normal position shown in Fig. —3— to permit the numeral to be withdrawn and substituted by another one if necessary.

The frame may be fastened to the building by nails, screws, screw-eyes or screw-hooks, any of which may be passed through apertures as —8'— in the upper rails as shown in Fig. —1— but it is evident that other fastening devices may be used through the same apertures if desired.

What I claim is:

A number plate comprising a substantially rectangular frame of sheet metal having lower and upper rails provided with grooves in their backs and slots leading from said grooves through the front sides of the rails, separate sheet metal numerals extending across the opening in the frame and having their lower and upper ends provided with bendable tongues inserted through slots and clenched against the backs of the rails within the grooves, the intermediate portions of the said tongues being offset forwardly to form shoulders for engaging the inner front corners of the rails.

In witness whereof I have hereunto set my hand this 2nd day of November, 1918.

WILLIAM H. HETZEL.
